UNITED STATES PATENT OFFICE.

WILLIAM HENRY WIGGINS, OF LAPLAND, KANSAS.

CULTIVATOR.

SPECIFICATION forming part of Letters Patent No. 395,098, dated December 25, 1888.

Application filed July 25, 1888. Serial No. 281,026. (No model.)

To all whom it may concern:

Be it known that I, WILLIAM HENRY WIGGINS, a citizen of the United States, residing at Lapland, in the county of Greenwood and 5 State of Kansas, have invented a new and useful Improvement in Cultivators, of which the following is a specification.

My invention relates to an improvement in cultivators; and it consists in the peculiar 10 construction and combination of devices that will be more fully set forth hereinafter, and particularly pointed out in the claims.

In the accompanying drawings, Figure 1 is a perspective view of a cultivator embodying 15 my improvements. Fig. 2 is an elevation of the same. Fig. 3 is a vertical transverse section of the same, taken on the line $x-x$ of Fig. 2. Figs. 4 and 5 are detail views.

A represents the tongue, on which at suitable 20 distances from its rear end are secured longitudinally-movable sleeves or boxes B. The same are connected on their under side by means of a rod, C, which is arranged directly under the tongue.

25 D represents a transverse arm or bar, the central portion of which is secured on the tongue by means of a clip, E. The said transverse arm or bar is preferably made of a piece of gas-pipe or water-pipe, and the ends 30 thereof are curved downward and extended in a vertical direction and form sockets for vertical arms F, which project upward from bearings or boxes G. Said arms or spindles F are swiveled in the sockets at the lower 35 ends of the cross arms or bars D by means of transverse pins H, which operate in segmental horizontal slots I in the ends of the cross bar or arm.

K represents a pair of axles, which are preferably square in cross-section and on which are secured circular concavo-convex disks L. Sleeves M of suitable length are slipped on the said axles and caused to bear between the said disks, so as to secure the same at 45 suitable regular distances apart. The said axles K are rounded at suitable points near their inner ends, and said rounded portions of the axles are journaled in the swiveled bearings or boxes G. The outer ends of the said 50 axles are also rounded and reduced in diameter, and are journaled in bearings N, which

are formed in the central portion of plates or shoes O, the ends of which are curved upward, as shown.

The concave sides of the disks on the two 55 axles are arranged opposite to each other, and thereby the said disks are adapted to throw the earth inward toward the center of the machine when the same is in operation.

P represents a pair of brace-rods, which have 60 their front ends bolted to opposite sides of the tongue A, and which diverge rearward and have their rear ends rigidly secured to the ends of the arched arm or cross-bar D, the function of these brace-arms being to 65 secure the said arm or cross-bar rigidly in position.

The front ends of the shoes or plates O are connected to the front sleeve or box, B, by means of link-rods R, and the rear ends of 70 said plates or shoes are connected to the rear sleeve or box, M, by means of link-rods S.

T represents draft-rods, which have their rear ends secured to the bearings G, and which extend forward therefrom and are adapted 75 for the attachment of the evener-bar or whiffletree, to which the team is hitched in the usual manner.

U represents a hand-lever, which is fulcrumed on one side of the beam and has its 80 lower end pivotally connected to the rod C. The said hand-lever bears against one side of a segment-plate or curved rack-bar, V, and is further provided with the usual spring-actuated locking-bolt, W, which is adapted to engage 85 the said segment-plate and thereby secure the hand-lever at any desired position.

The operation of my invention will be very readily understood. When the hand-lever is moved, the same imparts longitudinal movement through the sleeves or boxes B to the rod C, and the link-rods which are attached to the longitudinally-movable sleeves or boxes and to the shoes or plates O, at the outer end of the axle K, serve to turn the 95 said axles in a horizontal plane, so as to arrange the disks at any desired angle obliquely with relation to the line of draft.

When in operation, the machine is caused to run astride of the rows of plants, and by 100 reason of the concave sides of the disks on the two axles being presented to each other

the same are caused to thoroughly stir and pulverize the soil and throw the same toward the row of plants.

A seat, X, for the driver is supported over 5 the tongue A by means of a spring-bar, Y.

Having thus described my invention, I claim—

1. The combination of the tongue, the cross-bar D, secured thereon and having the down-turned ends, the brace-bars P, connecting said ends to the tongue, the bearings G, swiveled in the ends of the cross-bar, the axles journaled near the inner ends in said bearings and having the concavo-convex disks, the 15 plates O, journaled to the outer ends of the axles, the sliding boxes or sleeves on the tongue, the link-rods connecting said boxes to the plates O, the lever to operate the said boxes or sleeves, and the draft-rods T, attached to bearings G, substantially as described.

2. The combination of the tongue, the cross-bar secured thereto and having the down-turned tubular ends provided with horizontal 20 segmental slots I, the bearings G, having the

stems F in the lower ends of the cross-bar, the pins H, working in slots I and secured to the stems, the axles journaled in the bearings G and having the disks, the longitudinally-movable boxes or sleeves on the tongue, the 30 link-rods connected to said boxes or sleeves and to the axles, for the purpose set forth, and the lever to operate the boxes or sleeves, substantially as described.

3. The tongue, the cross-bar or arm D, secured thereon and projecting outward transversely on each side of the tongue, the separate axles journaled in bearings fitted on the ends of the cross-bar D, the longitudinally-movable sleeves B on the tongue, the sets of 40 disks on the axles, and the connecting-rods between the sleeves B and the separate axles, as set forth.

In testimony that I claim the foregoing as my own I have hereto affixed my signature in 45 presence of two witnesses.

WILLIAM HENRY WIGGINS.
